UNITED STATES PATENT OFFICE.

GUSTAVUS A. VON SHOLLY, OF FLUSHING, NEW YORK.

LAST-BLOCK FASTENER.

SPECIFICATION forming part of Letters Patent No. 367,870, dated August 9, 1887.

Application filed March 21, 1887. Serial No. 231,788. (No model.)

To all whom it may concern:

Be it known that I, GUSTAVUS A. VON SHOLLY, a citizen of the United States, residing at Flushing, in the county of Queens and State of New York, have invented a new and useful Improvement in Lasts, of which the following is a specification, reference being had to the accompanying drawings.

My invention relates to improved means of fastening the block to a boot or shoe last; and it consists in the construction and arrangement of the parts of the same, which will be more fully hereinafter described, and pointed out in the claims.

15 The object of my invention is to provide a semicircular locking-plate, which is secured to the last and adapted to engage with the block, the said plate being mounted in a circular recess formed partially in the top of the last and partially in the block, and having an operating-handle projecting above the top surface of the last and block. I attain this object by the construction illustrated in the accompanying drawings, wherein like letters of reference indicate similar parts in the several views, and in which—

Figure 1 is a perspective view of a last with my improved form of locking-plate shown in connection therewith. Fig. 2 is a top plan view of the same. Fig. 3 is a longitudinal vertical section of the last and block, with the plate in a locked position. Fig. 4 is a top plan view, looking at the rear, and showing the plate unlocked.

35 A indicates a last having the usual form of block, B, mounted in connection therewith. On the top portion of the last A and block B a circular recess, a, is formed, a portion of which is situated in the last A and a portion 40 in the block B. A semicircular plate, C, is pivotally mounted in the said recess a by means of a screw, S, passing therethrough and into the last A.

The plate C is constructed with a central 45 curved projection, c, through which the screw

S passes, and on each side of the said projection c rectangular-shaped slots c' c' are formed, which are adapted to engage with a pin or stud, c², screwed in the last A, on one side of the projection c, and adapted to form a guard-stop, so as to prevent the plate C from being turned to lock or unlock the block B in but one direction only, as shown by the arrow in Fig. 2. The plate C is also provided with an operating-handle, c³, which projects above the top surface of the last, so that it may be readily grasped for the purpose of operating the plate C.

When the plate C is turned in a locking position, as shown in Fig. 3, a portion thereof 60 rests on the block B and a portion on the last, so that a clamping between the block and last is obtained.

The screw S passes through the plate C, as hereinbefore described, and then passes into 65 an internally screw-threaded socket, S', as shown in Fig. 3, whereby a metallic bearing is formed for the said screw.

The novelty and utility of my invention being obviously apparent, it is unnecessary to 70 further enlarge upon the same herein.

Having thus described my invention, what I claim as new is—

1. The combination, with the last A and block B, having a circular recess, a, a portion of which is arranged in each of said parts, of the semicircular locking-plate C, pivotally screwed to the last A, and having slots c' c' on each side of the pivotal point of the said plate, the stud or pin c², secured to the last A, and with which 80 the slots c' c' engage, and the operating-handle c³, substantially as described.

2. In a last-block fastener, the semicircular pivotally-mounted locking-plate C, having the slots c', in combination with the stud or pin 85 c², substantially as described.

GUSTAVUS A. VON SHOLLY.
